UNITED STATES PATENT OFFICE

93,598

DESIGN FOR A SHOE

Arthur Apt, Roxbury, Mass.

Application June 25, 1934, Serial No. 52,333

Term of patent 3½ years

To all whom it may concern:

Be it known that I, ARTHUR APT, a citizen of the United States, residing at Roxbury, in the county of Suffolk and State of Massachusetts, have invented a new, original, and ornamental Design for a Shoe, of which the following is a specification, reference being had to the accompanying drawing, forming part thereof.

I claim:

The ornamental design for a shoe as shown.

ARTHUR APT.
